(57) **CLAIM**

The ornamental design for an external hard disk drive, as shown and described.

DESCRIPTION

FIG. 1 is a perspective view of an external hard disk drive, showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view of the external hard disk drive of FIG. 1, shown in an alternate configuration.

The broken lines in the drawings depict portions of the external hard disk drive that form no part of the claimed design.
